(57) CLAIM

The ornamental design for a heel clip, as shown and described.

DESCRIPTION

FIG. 1 is a rear perspective view of the heel clip disposed on a shoe;

FIG. 2 is a medial side view of the heel clip;

FIG. 3 is a lateral side view of the heel clip;

FIG. 4 is top view of the heel clip; and,

FIG. 5 is a rear view of the heel clip.

The heel clip is shown disposed on a left shoe. A heel clip on the right shoe is a mirror image of the heel clip on the left shoe. The shoe is shown in uneven broken lines for illustrative purposes only and forms no part of the claimed design.
